BUCKLE

Sidney A. Getts, Rockford, Ill., assignor of one-fourth to Warren B. Thayer, Rockford, Ill.

Application August 21, 1935, Serial No. 37,135

11 Claims. (Cl. 24—178)

The invention relates to buckles and has particular reference to a resiliently extensible buckle for providing a yieldable connection between the ends of a strap or belt.

- 5 One object of the invention is to provide an improved extensible buckle which is simple and sturdy in construction, attractive in appearance, and which is relatively inexpensive to manufacture.
- 10 Another object is to provide an improved extensible buckle requiring a minimum number of parts which are adapted to be assembled by simple and easily performed operations.

- Another object is to provide an improved extensible buckle wherein both the frame and the tongue of the buckle are extensible longitudinally so that the tongue may conform to the changing length of the frame and thereby maintain the proper relative position of the parts at all times.
- 20 Other objects and advantages will become apparent from the following detailed description taken in connection with the accompanying drawing, in which

Figure 1 is a perspective view of the preferred form of the buckle embodying the features of the invention.

Fig. 2 is a sectional view through the frame of the buckle shown in Fig. 1.

Fig. 3 is a plan view of a modified form of the 30 buckle frame.

Fig. 4 is a view partly in section of another modification.

Fig. 5 is a perspective view of the tongue shown in Fig. 1.

35 Fig. 6 is a perspective view of a modified form of the tongue.

Fig. 7 is a fragmentary sectional view taken along the line 7—7 of Fig. 3 and including a part of the strap for the buckle.

40 In carrying out my invention, I construct the buckle with a suitable shaped closed frame 7 having one end formed to facilitate attachment of the end of a strap or belt 8 thereto. The strap 8 may be secured to the frame in any suitable manner as by looping the end over a part of the frame and riveting or otherwise securely attaching the end to the body of the strap. Pivottally or otherwise suitably secured to the same part of the frame is a tongue 9 adapted to enter holes 6 in the opposite end of the strap and to engage with an oppositely disposed part of the frame 7 to hold the ends of the strap together.

45 To provide a degree of resiliency between the connected ends of the strap, I constructed the

frame 7 for expansion longitudinally under tension as applied to the strap and to return to its normal position when the tension is relieved. For this purpose, the frame is preferably constructed of two separate members suitably joined together by one or more tubular means constructed of resiliently extensible material.

5 In one form of the buckle as shown in Figs. 1 and 2 of the drawing, the frame 7 comprises two generally U-shaped members 10 and 11 connected by a coiled tension spring 12 to form a closed rectangular loop. The members 10 and 11 may conveniently be formed from wire stock bent to the desired shape. The coiled tension spring 12 is preferably formed with an internal diameter 15 such as to snugly receive the members 10 and 11. In assembling, the member 10 is first inserted in the spring and moved into a position such that substantially equal portions of the spring project beyond the respective legs of the member. The 20 projecting spring ends are then slipped over the ends of the member 11 and are secured to the transverse portion of the member by soldering or otherwise at points spaced so as to define a bearing for the tongue 9.

25 For attaching the tongue 9 to the frame, the tongue is preferably constructed with an eye 13 at one end. The eye may be partially formed so as to be readily slipped over the member 11 after assembly of the frame and it is then secured in place by bending the end portion back upon the body portion of the tongue.

30 To render the tongue 9 extensible longitudinally, it is constructed of two elongated elements mounted for movement relative to each other. One element numbered 14 and having the eye 13 formed therein is provided with a pair of outwardly and forwardly projecting ears 15 on the end opposite the eye 13. The other element 16 is likewise provided at one end with a similar pair of projecting ears 17. In both cases, the ears are spaced apart to define a channel adapted to receive the companion element. The two elements may thus be assembled together and the ears of each element bent inwardly over the other element to provide a sliding engagement therebetween. It will be apparent that the tongue so constructed may be readily extended to a limit determined by engagement of the ears 15 and 17.

35 40 45 50 55 The end element 16 of the tongue is preferably formed at its free end to provide a hooked portion 18 which is curved to follow the general contour of the end portion of the buckle frame 7. For a purpose to appear later, the portion 18 is

offset slightly from the body of the tongue so as to define a shoulder 18^a.

In the modified form of buckle shown in Fig. 3, rubber is utilized to provide the resilient connection between the frame members 10 and 11. Preferably, the rubber is incorporated in a strip of fabric folded upon itself with its edges joined at seam 20 to form an elongated tube 21 enclosing the members 10 and 11. The ends of the tube 10 may be fastened frictionally to the center of the member 11 by tubular clip 22 upon which the eye 13 may be pivoted. It will be observed that the elastic tube 20 provides for resilient extension of the buckle frame in the same manner as the spring 12 and at the same time lends a neat and attractive appearance to the buckle as a whole.

Figure 4 shows a modification in which coiled springs 23 form the side members of the buckle frame and snugly receive at their opposite ends 20 the short legs 26 and 27 of the U-shaped end members 24 and 25. Frictional engagement will ordinarily be sufficient to fasten the springs and end members together since the gripping action increases automatically as the springs are extended. However, if desired, solder may be applied at these joints.

Also shown in Fig. 4 is a tongue 9^a which differs from the tongue 9 previously described in several respects but which may be substituted therefor in any of the modifications of the buckle herein described. Tongue 9^a comprises a base portion 28 formed with an eye for attaching the same to the frame member 24. The element 28 is provided with a projecting stud 29 adapted to be frictionally secured to a coiled tension spring 30. Secured to the opposite end of the spring 30 is an end element 31 suitably formed to enter the holes in the strap 8 and to engage the frame member 25. It will be apparent that the length of the 40 tongue will vary as the spring 30 expands and contracts.

In the modified construction of the tongue 9^b as shown in Fig. 6, the end element 32 of the tongue is substantially similar to the element 15 of the tongue 9 (Fig. 5). Preferably, however, the projecting ears 33 are of substantial width to insure proper alinement of the tongue elements. The base element 34 is also of the same general construction as the element 14 of the tongue 9 except that the projecting ears for enclosing the element 32 have been dispensed with. Instead, the end of the element 34 opposite the eye 13 is folded back to form an abutment 35 which is engageable with the ears 33 of the member 32 to limit the movement thereof with respect to the base member.

The operation of the buckle constructed in accordance with the invention will be readily understood with reference to Fig. 1 of the drawing. 60 With the buckle connecting the ends of a strap 8 as shown, it will be apparent that when the strap is placed under tension, the connecting spring at 12 will yield and permit the frame 1 to be extended longitudinally. Likewise, the tongue 9 will, due to the engagement of its end 18 with the strap, follow the expansion of the frame so that the end will engage the end of the buckle frame at all times. The ends of the strap will thus be resiliently, yet securely, held together. Upon the 70 release of the tension on the strap, the spring 12 will contract and draw the members of the frame and likewise of the tongue back to their normal position as shown in the drawing.

In the forms of tongue shown in Figs. 5 and 6, 75 the extensibility of the tongue is limited by en-

gagement of the lugs 15 and 17 or 33 and 35. When the buckle has been extended to this limit, the tendency of the tongue end 18 to pull out of the strap hole is prevented by virtue of the engagement between the strap and the tongue shoulder 18^a. In this way, extensibility of the buckle is positively limited thereby preventing the resilient connecting element from being stressed beyond its elastic limit.

From the foregoing, it will be apparent that I have provided an improved extensible buckle which is simple and sturdy in construction and attractive in appearance. The buckle comprises relatively few parts which may be manufactured at low cost and readily assembled. Through the provision of the extensible tongue, the buckle frame may expand and contract according to the degree of tension placed thereon simply by elongation of the springs and relative movement between the tongue parts. Expansion and contraction of the buckle therefore occurs without frictional wear on the strap.

I claim as my invention:

1. A buckle for resiliently connecting the ends of a strap or belt, said buckle comprising a longitudinally extensible frame, and an extensible tongue pivotally supported on one end of the frame and extending to and engaging the opposite end of the frame, said tongue comprising two members movable relative to each other for varying the length of the tongue to conform to varying lengths of the frame.

2. A buckle for resiliently connecting the ends of a strap, said buckle having a frame comprising a pair of generally U-shaped members resiliently joined together to form a closed rectangle, one of said members having attached thereto one of the ends of the strap, and an extensible tongue pivotally attached to said one member and extending toward the other member, said tongue having an end portion adapted to enter a hole in the other end of the strap and to engage said other member.

3. A buckle for resiliently connecting the ends of a strap, said buckle having a frame comprising a pair of generally U-shaped members resiliently joined together to form a closed rectangle, one of said members having attached thereto one of the ends of the strap, and an extensible tongue pivotally attached to said one member and extending toward the other member, said tongue comprising one element attached to said one member and a second element movable relative to said one element and adapted to enter a hole in the strap and be held by the strap in engagement with said other member whereby the tongue conforms at all times in overall length to varying lengths of the frame.

4. A buckle for resiliently connecting the ends of a strap or the like, said buckle having a longitudinally extensible frame and a correspondingly extensible tongue, said frame comprising a pair of generally U-shaped end members one of which is adapted to be attached to an end of the strap and to support said tongue, and a coiled tension spring enclosing the other of said end members and having its ends projecting over the respective ends of said one member and secured to the body of said one member on opposite sides of the tongue to provide a resilient connection between the two members.

5. A buckle for resiliently connecting the ends of a strap or the like, said buckle having a longitudinally extensible frame, and a correspondingly extensible tongue, said frame comprising a pair

- of generally U-shaped end members connected at opposite ends by coiled tension springs to define a closed rectangle, said tongue having a base portion attached to the body of one of the members
- 5 and an end portion connected with and movable longitudinally of said base portion whereby the said end portion remains in engagement with the other of said end members when the relative position of said end members is varied by the expansion or contraction of said connecting springs.
6. A buckle for resiliently connecting the ends of a strap or the like, said buckle having an extensible frame comprising a U-shaped end member, a resiliently extensible tube enclosing said member and having its opposite ends projecting substantially beyond the respective ends of the member, and a second U-shaped member having end portions entering into and secured to the projecting ends of said tube, and an extensible tongue carried by said second member and engageable with said first member.
7. A buckle for resiliently connecting the ends of a strap or the like, said buckle having an extensible frame comprising a U-shaped end member, a tube of rubber material enclosing said member and having its opposite ends projecting substantially beyond the respective ends of the member, and a second U-shaped member having end portions entering into and secured to the projecting ends of said tube, and an extensible tongue carried by said second member and engageable with said first member.
8. A buckle for resiliently connecting the ends of a strap or the like, said buckle having an extensible frame comprising a U-shaped end member, a strip of elastic fabric folded laterally and sewed along its edges to form a resiliently extensible tube enclosing said member and having its opposite ends projecting substantially beyond the respective ends of the member, and a second U-shaped member having end portions entering

into and secured to the projecting ends of said tube, and an extensible tongue carried by said second member and engageable with said first member.

9. A buckle for resiliently connecting the ends of a strap comprising two members defining the ends of a buckle frame, resiliently extensible elements connecting the ends of said members, a longitudinally extensible tongue connected at one end to one of said members and adapted at its other end to enter a hole in said strap and bear against the other member, and stop means acting to positively limit the extensibility of said tongue within the elastic limit of said connecting elements.

10. A buckle for resiliently connecting the ends of a strap comprising two members defining the ends of a buckle frame, resiliently extensible means connecting the ends of said members, a tongue element connected to one of said members, a second element connected at one end to slide longitudinally of said first element with its free end adapted to enter a hole in said strap and bear against the other of said members, said free end being offset to define a shoulder engageable with said strap to prevent relative longitudinal movement between said second tongue element and the member engaged thereby, and interengaging stops on said elements acting to limit the degree of extension of said tongue elements.

11. A buckle comprising, in combination, a longitudinally extensible open frame for receiving one end of a strap, and a tongue supported on said frame and arranged for engagement with said strap to hold the latter against movement relative to said frame, said tongue being constructed to extend and contract automatically as an incident to extension and contraction of said frame.

SIDNEY A. GETTS.
